UNITED STATES PATENT OFFICE.

JOHN KIGAS, OF CHICAGO, ILLINOIS, ASSIGNOR TO ALEX WASLEFF, OF CHICAGO,
ILLINOIS.

FLOOR AND SURFACING MACHINE.

Original application filed February 28, 1921, Serial No. 448,326. Divided and this application filed October 28, 1921. Serial No. 511,038.

To all whom it may concern:

Be it known that I, JOHN KIGAS, a citizen of Latvia, Russia, resident of Chicago, in the county of Cook and State of Illinois, have invented certain new and useful Improvements in Floor and Surfacing Machines, of which the following is a full, clear, and exact description.

My invention relates to means for regulating the pressure against the floor of the sandpapering or smoothing rollers of floor and surfacing machines constituting the subject-matter of an application for Letters Patent of the United States, filed by me February 28, 1921, Serial Number 448,326, of which this application is a division.

The object of this invention is to enable the sandpapering rollers to press evenly down against the floor when the machine is in operation so as to produce a smooth even surface that will avoid a corrugated appearance. This I accomplish by means herein-after fully described and as particularly claimed.

25 In the drawings:

Figure 1 is a side elevation of the machine to which this invention is applied.

Figure 2 is a horizontal section of the same, in which features not constituting parts of said invention are eliminated.

Figure 3 is a vertical longitudinal section taken on dotted line 3, 3, Figure 2.

Figure 1 of the drawings illustrates the machine to which my improvements are applied, although it will be understood that they can be applied to any floor smoothing machine so constructed as to permit their application. This machine possesses wheels that support and guide it, and means for actuating said wheels, and these wheels maintain the framework and other parts of the machine at a certain distance above the floor. My invention is carried by said framework and is designed to regulate the downward pressure of the smoothing rollers against the floor.

The supporting framework of the machine consists of parallel side sills A, A, that are tied together, preferably, by a platform B, and a transom C. The drive wheels D, D, are driven through suitable means by an electric motor E supported upon said plat-

form, and the guide-wheels F, F, are journaled on the ends of a transverse axle G.

Secured to the side sills, at their upper edges, are side-frames 5, 5, and just outside of said frame on one side of the machine are parallel aprons, 6 and 7, that are supported by bolts 8, 8, tapped into the side-frame.

Pivotedly secured to the sides of the side-frame are two pairs of levers 9, 9, and 10, 10, that extend longitudinally and are so arranged that the levers 9, 9, and 10, 10, are practically fulcrumed in alinement.

The ends of these levers, near the ends of the machine are provided with bearings 11, 11, for the journals of the shaft 12, projecting axially from the ends of the smoothing rollers 13, 13.

The fulcrums 14, 14, of levers 9, 9, and 10, 10, project out through longitudinal elongated openings 15, 15, therein, and have nuts 16, 16, tapped longitudinally into their outer ends to retain the levers in position.

The inner ends of these levers terminate before they reach the center of length of the machine and have links 17, 17, pivotally secured thereto, that extend vertically and have their upper ends pivotally connected to the ends of a walking-beam 18. This walking-beam extends longitudinally and, at its center of length is fulcrumed at 19 to the ends of a cross-bar 20. This cross-bar extends from side sill to side sill and its ends are seated in the side sills and it is limited to a vertical movement by means of pins 21, 21, extending downwards from its ends that enter openings 22, 22, in the side frames.

The journals of the armature shaft of the motor extend through their bearings on one side of the machine, and one of them has a sprocket-wheel 23, securely mounted thereon, and this sprocket-wheel is connected by a drive-chain, 24, to a sprocket-pinion, 25, and a sprocket-gear, 26, that give it a triangular course. The sprocket-gear 26 is securely mounted upon a transverse spindle, 26^a, the ends of which are journaled in aprons 6 and 7, and alongside of this sprocket-gear 26 is secured another gear, 27, that intermeshes with a corresponding gear 28 securely mounted upon a transverse spindle, 29, whose ends are journaled in said apron. Gear 27 is connected to a sprocket-wheel, 30, on the

end of the trunnion or journal of the shaft of the smoothing-roller at one end of the machine, by a sprocket-chain, 31, and alongside of gear 28, a suitable sprocket-wheel, 32, is secured on spindle, 29, and by a sprocket-chain, 33, is connected to a sprocket-pinion, 34, on the end of the trunnion of the smoothing-roller on the same side and at the other end of the machine.

- 10 When the machine is travelling in one direction and some obstruction is met and ridden over by the smoothing-roller, the opposite smoothing-roller will be pressed downwards, and when it is desired to raise both 15 of said rollers, the pressure of the foot of the operator upon the cross-bar 20 will cause both of said rollers to move upwards.

The ends of the levers nearest the ends 20 of the machine are kept pressing downwards by vertically disposed contraction springs 35, 35. The lower ends of these springs terminate in seats 36, 36, in the top of the bearings of the levers, and the upper 25 ends of the springs are articulated with rings in the lower ends of the ring-bolts 37, that extends upward through lugs, 38, and are provided with nuts 39, on their screw-threaded ends above said lugs.

30 My invention will best serve the purpose of its construction by making the smoothing-rollers very yielding. This I accomplish by the means hereinabove described, but I do not wish to be limited to these means, as an 35 expert mechanic, when he is made to realize the objects and purposes of the use of the smoothing-rollers, may be able to devise modifications of the means I have hereinabove described.

What I claim as new is:

- 40 1. A sandpapering machine comprising a suitable supporting-frame, means for propelling the same, transversely disposed rotatable abrading drums, and devices for con-

trolling the pressure of said drums against the surface of the floor over which the machine is travelling so that when one roller moves over an obstacle the other will move downwards and so that the operator can move said rollers simultaneously downwards. 45

2. A sandpapering machine comprising a 50 suitable supporting-frame, a motor mounted thereon, longitudinally disposed levers fulcrumed to the sides of said supporting-frame, transversely disposed abrading rollers journaled in bearings in the ends of said levers adjacent to the ends of the machine and means consisting of links and a walking-beam for connecting the adjacent ends of levers on the same side of said machine. 55

3. A sandpapering machine comprising a 60 suitable supporting-frame, a motor mounted thereon, longitudinally disposed levers longitudinally adjustably fulcrumed to the sides of said supporting-frame, transversely disposed abrading rollers journaled in bearings in the ends of said levers adjacent to the ends of the machine and means connecting the adjacent ends of levers on the same 65 side of said machine. 70

4. A sandpapering machine comprising a 75 suitable supporting-frame, a motor mounted thereon, longitudinally disposed levers longitudinally adjustably fulcrumed to the sides of said supporting-frame, transversely disposed abrading rollers journaled in bearings in the ends of said levers adjacent to the ends of the machine and means consisting of links and a walking-beam for connecting the adjacent ends of levers on the same side of said machine. 80

In witness whereof, I hereunto set my hand and seal this 18th day of October, 1921.

JOHN KIGAS.
